UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

SEWING-MACHINE FEEDING AND RUFFLING MECHANISM.

1,156,545.

Specification of Letters Patent.

Patented Oct. 12, 1915.

Application filed November 18, 1903. Serial No. 181,660.

To all whom it may concern:

Be it known that I, LANSING ONDERDONK, a citizen of the United States, residing at New York city, in the county of New York, State of New York, have invented certain new and useful Improvements in Sewing-Machine Feeding and Ruffling Mechanism, of which the following is a description, reference being had to the accompanying drawing, and to the letters and figures of reference marked thereon.

My invention relates to improvements in sewing machines and particularly to those of the blind stitch type, such as illustrated for example in my application for Letters Patent, filed Dec. 31, 1901, Serial No. 87,959.

In an application filed by me on the 30th of October, 1902, Serial No. 129,397, patented April 18th, 1911, No. 990,160 I have shown, described and claimed a top feed mechanism for use on machines of the general type referred to, which can also be adapted for ruffling or gathering, and the present invention, in so far as certain features are concerned, presents an improvement on the construction illustrated in such application; a different arrangement and location thereof, a different character of feeding dog, a means of adjustment to vary the throw with respect to the lower feed dogs, so as to gather or full in a portion of the goods. In other respects the present invention sets out more elaborately various details of construction not heretofore set up and claimed in said other applications.

At the outset I would state that the main features of the present machine are fully set forth in the above application Serial No. 87,959; the looper movement in application Serial No. 81,765, filed Nov. 9, 1901; patented December 7th, 1908, No. 926,891 the work plate operating mechanism in application 87,958, filed Dec. 31, 1901; patented December 31st, 1901, No. 745,736 the upper feed substantially as illustrated in Figure 8 of the present case, in my above mentioned Patent No. 990,160, dated April 18th, 1911, and the main or lower feeding mechanism in my application filed July 31, 1902, Serial No. 117,878, patented October 22d, 1912, No. 1,042,258.

My invention consists in the parts and arrangements hereinafter described, and set forth in the claims.

The invention is illustrated in the accompanying drawings, in which—

Fig. 1 is a front elevation of a blind stitch sewing machine embodying my invention in its preferred form; Fig. 2 is a front perspective thereof, the standard and base 60 of the machine being removed; Fig. 3 is a top plan view of the work support and top feed mechanism, the gooseneck; needle and looper mechanisms and presser foot being removed; Fig. 4 is a detail front view of 65 the left hand portion of Fig. 1; Fig. 5 is a detail perspective view of the supplemental feeding or ruffling mechanism, and a portion of the main feeding mechanism; Fig. 5^a is a detail view showing the connections between 70 the operating shaft and the rocking frame which carries the top feeding mechanism; Fig. 5^b is a detail in perspective showing the locking latch for the upper feed dog. Fig. 6 is an end view of Fig. 2, parts being 75 broken away; Fig. 7 is a rear view of the top feed or ruffling mechanism; Fig. 8 is a rear perspective view of the main and supplemental feeding mechanisms, the latter being applied to the front instead of to the 80 rear of the machine and a somewhat different supporting framework being used this being a modified form of the invention. Fig. 9 is a detail perspective of another type of supplemental feeding or ruffling device and 85 adjustment therefor.

In these drawings, A is the standard of a blind stitch sewing machine, B the overhanging arm or gooseneck, and C the work supporting plate herein shown as a cylindrical casing inclosing the lower or main feeding mechanism.

D is the throat plate having openings for the passage of the two feed dogs 1, the openings being located upon opposite sides 95 of the rib or projection E over which the goods to be stitched are crimped.

The needle 2 reciprocates in a curved path transversely to the line of feed and is operated from the driving shaft in the manner set forth in my application 87,959 through the rocking arm 3 and pitman con-

nection 4 to the driving shaft 5. The looper L is secured in a collar or clamp 15 on the lower end of the rod 11 which rod has a lower part 13 screwed into a socket in the upper part 12, which upper part 12 is pivoted between the forks of a pin or bolt 10 pivoted to a crank 9, on the rock shaft 6 journaled in the bearing barrel 7 on the head of the machine. This rock shaft has at its opposite end a crank having pitman and eccentric connection to the driving shaft. The rod 13 through the action of the cranks on the rock shaft 6, is raised and lowered to impart to the looper a rise and fall to enable it to pass from one side the line of seam to the other, over the apex or ridge on the throat plate and to enable it to escape obstructions, such as seams or extra thicknesses of goods. To impart, however, this side-wise movement from one side the line of seam to the other, it is necessary to freely pivot or fulcrum the looper supporting rod, in order that as it rises and falls and the cranks pass from one side the center to the other, a tilting movement may be imparted and to this end I have provided the arm 16 enlarged at its outer end and formed with a recess through which the rod 13 passes, this recess being formed to receive and hold a ball bearing 17. In the rise and fall therefore, of said looper supporting rod, it slides through the ball 17 and at the same time oscillates said ball in its support, whereby the looper has the four motions above referred to. It is also necessary to impart to said looper a forward and backward movement in the direction of its length to enable it to take and leave the needle loop and also carry its own loop into position to be engaged by the needle and to this end the arm 16 at its inner end is fixed upon an upright rock shaft 18 journaled in bearing lugs 19 and 20 on the machine frame. The upper end of this rock shaft 18 has clamped about it one end of a rod or bar 21, which at its opposite end has a ball and pitman connection 22, 23, with an eccentric on the main shaft. As the shaft revolves therefore, the vertical rock shaft is oscillated and the bearing 24 through which the looper rod passes and in which it is fulcrumed, swings from front to rear of the machine, thus imparting to the looper, a forward and backward movement in the direction of its length.

Referring now to the feeding mechanism shown in Fig. 8, *u* represents the feed shaft which imparts the forward and backward movements to the feed dogs 55 while shaft *u'* gives the vertical movements thereto through the link 54 fixed to its outer end and pivotally attached to the bar 52.

The numeral 55 represents two feed dogs having teeth in their lower forward edges, these being fixedly sleeved at the front of the machine to a shaft 59 extending longitudinally of the work support, and journaled in the upper ends of arms 60, 60, fixed at their lower ends to the rock shaft 61 journaled in bearings in a lug 62 secured to the work support. This rock shaft is provided with an upwardly and outwardly extending arm 63 to which, near its upper end is adjustably fitted in the slot *s* a bolt 64 upon which is pivoted one end of a link 65 which at its opposite end is pivoted on a bolt 66 secured to the upper end of the arm 67 which latter is at its lower end clamped upon the shaft *u*. It will be seen, therefore, that as the shaft *u* oscillates the shaft 61 rocks and swings the arms 60 bodily, thus moving the feed dogs 55, bodily back and forth. Near its inner end the shaft 59 has fixed upon it, a downwardly projecting arm 68, which at its lower end is provided with a stud 69, upon which is pivoted one end of a curved link 70, which, at its lower end, is pivoted on the stud 71, secured on the lower end of the lever or crank 72, loosely sleeved on the shaft *u'*. This lever or crank 72 is normally pinned to the crank 73 fixed at its upper end to the shaft *u'*. This pinning together of the two cranks is accomplished by means of a spring catch 74 pivoted to the crank 73 and having a latch engaging the slot 75 in the crank 72. When the cranks 72 and 73 are pinned together and move as one, the oscillation of the shaft *u'* transmits an oscillatory movement to the shaft 59, thus swinging the forward ends of the feed dogs up and down. When the catch 74 is withdrawn from engagement with the crank 72, a leaf spring 75 secured in the split end of the shaft 59 and bearing at its lower end between the projections 77 on the arm 68 swings the lower end of said arm forward and thus automatically raises the forward ends of the dogs. Means are provided for automatically releasing the top feed mechanism when the work plate is lowered for the insertion or removal of the work and to this end the spring catch 74 has its lower end projecting downwardly into position to be engaged by a projection 770 on the machine standard, whereby when the work support is lowered, the catch will be tripped and release the crank 72 from engagement with the crank 73, holding the catch in its engaged position until the work support returns to elevated position and the shaft *u'* begins to oscillate when the cranks are again united.

In Fig. 9 an arrangement for simple ruffling is shown in which a ruffling blade 101 is attached to the end of a rod or shaft 59' which is secured near the upper end of the arm 63' pivoted at its lower end upon the rock shaft 61. The arm 67 in this figure corresponds to the arm 67 in Fig. 8 and is oscillated by the shaft *u*, motion being transmitted from the arm 67 to the arm 63' by 130

means of the link 65 having a bolt connection with the curved slot 100 in the arm 63'. By this arrangement, it will be noticed that the adjustment of the arm 65 up and down in the slot 100 varies the amount of throw in the ruffler blade 101.

The preferred form of top feed mechanism which I use is illustrated in Figs. 1 to 7 of the drawings and upon this I propose to base specific claims in the present application. In these figures 59" corresponds to the shaft 59, this having clamped to its outer end the plate 102 which extends beneath the head of the machine and has removably secured to it a top feed dog or ruffling member 103 which projects forwardly toward the needle of the machine.

61' represents a shaft corresponding in Fig. 8 to the shaft 61, this being journaled in bearings upon the brackets 104 secured to the bed plate of the machine and being connected with the shaft 59" by the upright arms 60' 60", the arm 60" having therein a curved slot to receive the adjustable bolt 64' upon which is pivoted the link 65' which at its other end is pivoted upon the stud 66 secured to the arm 67, which at its lower end is clamped to the shaft n'. By this series of connections the feed dog 103 is moved back and forth as the shaft n' oscillates. In order to give the rise and fall to the feed dog supporting plate 102 and therefore to the feed dog 103, there is sleeved on the shaft 59" the link 105 to which is pivoted a downwardly projecting link 106 which at its lower end is pivoted by means of the stud 107 to the arm 108 which is loosely sleeved on the rock shaft n'. This arm 108 is slotted as shown at 75' to receive a catch 74' pivoted to the crank 73' clamped on the shaft n', this catch 74' being normally spring pressed to engage the slot in the arm 108 by means of the spring 109. The operation of the parts is substantially the same as described, in connection with Fig. 8, for when the catch 74' is in normal position, it engages the slot 75' in the arm 108 and pins the crank 73 and arm 108 together, thus transmitting movement through the link 106 to the crank or link 105, thus raising and lowering the top feed dog supporting frame, as the shaft n' is oscillated. A spring 750' is secured at one end in a slot in the end of the shaft 59" and at the other end between extensions 110 on the link 105 and its tension is adjusted by means of the upper and under blocks 111 and screw 112 and this spring permits the automatic rising of the top feed frame when the work support is lowered and the catch 74' engages the projection 770 to throw the catch 74' out of engagement with the arm 108.

Carried by the top feed frame and attached to a projection 113 thereon is a part shown at 114 which projects forwardly to a

point just over the top feed dog. This part 114 of course partakes of all the movements of the top feed dog and its object is to turn down the ravelings or threads projecting from the raw edge of the material being sewed, while the stitch is being formed.

It will be seen from the small plan view at the left of Fig. 5, that the finger formed on the top of the feed dog projects under the forward end of the member 114, and that the main portion of said feed is in front of said member. As the fabric passes from under said top feed, the loose thread ends or ravelings are liable to project out between the threads of the stitches unless they are turned down flat upon the fabric. The member 114 has the forward end thereof curved so that as said member is moved over the fabric, the forward end thereof will turn down any ravelings or threads projecting from the raw edge of the material. The stitches are then laid over said turned down threads. This part 114 is independent of the top feed dog 103, so that the looper thread loops and the needle thread loops may be drawn down between these parts to the underside of the part 114, thus covering the ravelings held down by said part 114. The opening 115 near the end of the part 114 is for the purpose of relieving the interlocked loops of the stitching threads from pressure at the time said loops are drawn on to set the stitch. This top feed dog 103 is provided with a tongue 116 over which the stitch is formed. This, however, is not absolutely essential when the part 114 is used. The underside of the part 114 at the point nearest the path of the needle is made so as not to press heavily upon the material sewn and therefore will not interfere with the drawing of the stitch taut.

It will be seen that by adjusting the top feed that a movement thereof in advance of the lower feed may be given to gather or full in the goods, which is desirable on certain classes of blind stitch work.

It will be noted that my top feeding mechanism may be either a ruffling blade or a serrated feed dog, and that either of these members may be moved in unison with the lower feeding mechanism or may be given a different movement so as to full or gather the material being operated upon. I have referred to this ruffling blade and feed dog throughout the claims as a feeding device, and it will be understood that this term is intended to cover either of these members whether coöperating with the lower feeding mechanism merely to feed the material in the usual way, or whether coöperating therewith to ruffle or gather the material.

Having thus described my invention, what I claim and desire to secure by Letters Patent, is:—

1. A blind stitch sewing machine includ-

- ing in combination a work support, a rib carried thereby for crimping the material, a needle reciprocating transversely of said rib, a looper coöperating therewith to form 5 stitches, and a feeding mechanism comprising two feed members located upon opposite sides of a horizontal plane passing through the needle at the stitching point, means for operating said feeding members and means 10 for relatively adjusting the movements thereof to impart differential movements thereto.
2. A blind stitch sewing machine including in combination, a needle, a looper coöperating therewith, means for crimping the material whereby said needle may enter and emerge on the same face of the material, a main feeding mechanism, a supplemental feeding mechanism operated from the main 15 feeding mechanism, and moving forward and backward and upward and downward, and means for adjusting the supplemental feeding mechanism independently of the main feeding mechanism, whereby the movements of the supplemental feeding mechanism may be varied with respect to the main feeding mechanism.
3. A blind stitch sewing machine including in combination, a work support, having 20 feed openings, a crimping ridge located between said feed openings, a needle reciprocating transversely of the line of feed, a looper coöperating with said needle, a main two part lower feed operating through said 25 openings in the work support, and adapted to engage the fabric upon opposite sides of the crimping ridge, and a top feeding device adapted to engage the fabric between the parts of the main feeding device.
4. A blind stitch sewing machine including in combination, a work support having feed openings, a crimping ridge located between said feed openings and carried by the work support, a needle reciprocating trans- 30 versely of the line of feed, a looper coöperating therewith, a main two part lower feed operating through the openings in said work support and adapted to engage the fabric upon opposite sides of the crimping 35 ridge, a top feeding device adapted to engage the fabric between the parts of the main feeding device, and means for adjusting the throw of the top feeding device independently of the main feeding device, 40 whereby a differential movement may be imparted to the two said feeding mechanisms.
5. A sewing machine including in combination, stitch forming mechanism, a work support having feed openings formed there- 45 in, a crimping ridge located between said openings, a main two part feeding mechanism, engaging the material on opposite sides of said crimping ridge through the 50 openings in the work support, a top feeding mechanism including a fabric engaging de- 55 vice bearing upon the ridge forming member, and means for operating the main and top feeding mechanism.
6. A sewing machine including in combination, stitch forming mechanism, a main two part feeding device, a crimping ridge located intermediate the parts of the main feeding device, a top feeding mechanism including a feeding device bearing upon the crimping ridge, means for operating the top feeding mechanism, said top feeding device having a tongue over which the stitches are formed.
7. A sewing machine including in combination, stitch forming mechanism, a main two part feeding mechanism, a crimping ridge located intermediate the parts of the main feeding device, a top feeding mechanism including a fabric engaging device bearing upon the crimping ridge, means for operating the main and top feeding mechanisms and presser members bearing upon the material upon opposite sides of the crimping ridge, and coöperating with the parts of the main feeding mechanism.
8. A sewing machine including in combination, stitch forming mechanism, a main feeding mechanism including fabric engaging devices, a crimping ridge located intermediate the fabric engaging devices, a top feeding mechanism including a fabric engaging device bearing upon the crimping ridge, means for operating the main and top feeding mechanisms, and a device in front of the top fabric engaging device, for turning and holding down the ravelings from the raw edge of the material being sewed.
9. A sewing machine including in combination, stitch forming mechanism, a main feeding mechanism, including fabric engaging devices, a crimping ridge located intermediate the fabric engaging devices, a top feeding mechanism including a fabric engaging device bearing upon the crimping ridge, means for operating the main and top feeding mechanisms, a device in front of the top fabric engaging device for turning and holding down the ravelings from the raw edge of the material being sewed, and means for moving the device for turning down the ravelings with said top fabric engaging device.
10. A sewing machine including in combination, stitch forming mechanism, a main feeding mechanism including fabric engaging devices, a crimping ridge located intermediate the fabric engaging device, a top feeding mechanism including a fabric engaging device bearing upon the crimping ridge, means for operating the main and top feeding mechanisms, a device in front of the top fabric engaging device for turning and holding down the ravelings from the raw edge of the material being sewed, and means for moving the device for turning

down the ravelings with said top fabric engaging device, said device for turning down the ravelings having a cut away portion at its outer end to leave the threads of the 5 stitches free from any pressure so that each stitch may be drawn tight in the formation of the succeeding stitch.

11. A blind stitch sewing machine including in combination, a needle reciprocating back and forth across the line of feed, a looper coöperating therewith, a top feeding mechanism comprising a plate extending from the rear toward the front of the machine, and having a fabric engaging device 10 attached thereto, and extending in proximity to the needle, a rocking frame on which said plate is supported, said rocking frame comprising upper and lower shafts, brackets on the machine frame in which said lower 15 shaft is journaled, arms supported at the lower ends on said lower shaft in which the upper shaft is supported, an adjustable means connected to one of said arms for imparting forward and backward movements 20 to said plate, and means connected to said upper shaft for imparting vertical movements to said plate.

12. A blind stitch sewing machine, including in combination, a needle reciprocating back and forth across the line of feed, a looper coöperating therewith, a top feeding mechanism comprising a plate extending from the rear toward the front of the machine, a fabric engaging device attached to 30 said plate and extending in proximity to the needle, a rocking frame on which said plate is supported, said rocking frame comprising upper and lower shafts, brackets on the machine frame in which said lower 35 shaft is journaled, arms supported at the lower ends on said lower shaft, and supporting said upper shaft, an oscillating shaft, adjustable connections between one of said arms and the oscillating shaft for imparting 40 forward and backward movements to the fabric engaging device, a second oscillating shaft, and connections between the said upper shaft and the oscillating shaft for imparting 45 vertical movements to the fabric engaging device, said connections including pivoted links 105, 106, an arm 108 and a crank 73, both said arm and crank being sleeved on said second oscillating shaft, and a movable catch for releasing the arm 108, from engagement with the crank 73.

13. A blind stitch sewing machine including in combination, a needle reciprocating back and forth across the line of feed, a looper coöperating therewith, a top feeding mechanism comprising a plate extending 50 from the rear toward the front of the machine, a fabric engaging device attached to said plate and extending in proximity to the needle, a rocking frame on which said plate is supported, said rocking frame comprising upper and lower shafts, brackets on

the machine frame in which said lower shaft is journaled, arms supported at the lower ends on said lower shaft and supporting said upper shaft, an oscillating shaft, adjustable connections between one of said arms and the oscillating shaft for imparting forward and backward movements to the fabric engaging device, a second oscillating shaft, and connections between the said upper shaft and the second oscillating shaft for imparting 70 vertical movements to the fabric engaging device, said connections including pivoted links 105, 106, an arm 108 and a crank 73, both said arm and crank being sleeved on said second oscillating shaft, and a movable catch for releasing the arm 108, from engagement with the crank 73. 75

14. A blind stitch sewing machine including in combination, a work support, means carried thereby for crimping the material, 80 stitch forming mechanism including a needle and means for reciprocating it transversely of the crimping means to cause it to enter and emerge on the same face of the fabric, and a feeding mechanism including two feed members, means for operating the same, and means for adjusting the movements of one of said feed members independently of the other, whereby a differential movement may be imparted to said two 85 feed members.

15. A blind stitch sewing machine including in combination, a work support, means carried thereby for crimping the material, 90 stitch forming mechanism including a needle with means for reciprocating it transversely of the crimping means to cause it to enter and emerge on the same face of the fabric, and a feeding mechanism including two feed members, means for operating the same, and means for adjusting the movements of one of said feed members independently of the other, whereby a differential movement may be imparted to said two 95 feed members, one of said members being located below the work support and operating upon the under surface of the fabric, and the other of said feed members being located above the work support, and operating upon the upper surface of the work. 100

16. A blind stitch sewing machine including in combination a work support, means carried thereby for crimping the material, 110 stitch forming mechanism including a needle with means for reciprocating it transversely of the crimping means to cause it to enter and emerge on the same face of the fabric, and a feeding mechanism including two feed members, means for operating the same, and means for adjusting the movements of one of said feed members independently of the other, whereby a differential movement may be imparted to said two 115 feed members, one of said members being located below the work support and having 120

two spaced feed engaging devices, and said other feed member being located above the work support and engaging the fabric between the said lower feed devices.

- 5 17. A blind stitch sewing machine, including in combination a work supporting member, a needle reciprocating from side to side of the line of seam above said work supporting member, means for operating said needle, and means in advance of the needle for turning and holding down the ravelings on the edge of the material being sewed.
- 10 18. A blind stitch sewing machine including in combination, a work support, a crimping ridge carried thereby, a needle, means

for reciprocating the needle back and forth across the crimping ridge, a feeding mechanism including an upper feed dog located directly over said crimping ridge, said feed dog having a centrally projecting tapering tongue on the forward end thereof adapted to intersect a vertical plane containing the path of movement of said needle.

In testimony whereof I affix my signature in presence of two witnesses.
